DRAWING PAGE UNAVAILABLE

DOCUMENT NUMBER

D18442

UNITED STATES PATENT OFFICE.

CHARLES E. HEYER, OF CHICAGO, ILLINOIS, ASSIGNOR TO BARNHART BROS.
& SPINDLER, OF SAME PLACE.

DESIGN FOR A FONT OF COMBINATION TYPE ORNAMENTS.

SPECIFICATION forming part of Design No. 18,442, dated July 10, 1888.

Application filed April 13, 1888. Serial No. 270,596. Term of patent 14 years.

To all whom it may concern:

Be it known that I, CHARLES E. HEYER, a citizen of the United States, residing at Chicago, county of Cook, and State of Illinois, 5 have invented and produced a new and original Design for a Font of Combination Type Ornaments, which is set forth in the following specification, reference being had to the accompanying typographical impressions, which are exact representations of said design.

This design comprises a group of ornaments adapted to be combined, and the font comprises the following pieces: 0, three parallel fine lines; 1, heavy dotted wave line between 15 two lighter wave lines; 2, medium-weight serpentine line ending in an arrow; 3, single medium-heavy serpentine line; 4, three fine wave lines approximately but not entirely parallel; 5, three heavy wave lines approximately but not entirely parallel; 6, heavy dotted wave line between shorter light wave lines; 7, three medium heavy wave lines, the middle one longer and extending farther to the left than the outside ones; 8, five fine wave 25 lines; 9, five medium-heavy wave lines, every other line dotted and every other line solid; 10, three medium-heavy wave lines, the middle longer than the others and extending farther to the right, the other lines ending in small scrolls; 11, medium heavy dotted wave line, and both above and below two medium-heavy lines, the first solid and the second dotted, the five lines tapering toward the left to the middle line; 12, three fine-line parallel quarter-circles; 13, five diverging wave lines 35 tapering to the middle one to the right; 14, an upright wave line and three broken circumflexes extending to the left; 15, five circumflexes extending to the right with dots between each two; 16, three broken wave lines extending to the right and diverging; 17, a medium-heavy straight line above three arcs, diverging to the left, each alternate line being light and each alternate one heavy; 18, a straight 40 line above three arcs, diverging to the right, and each alternate line being light and each alternate line heavy; 19, a medium-heavy straight line above three arcs, diverging to the left, each alternate line being heavy and each alternate line being light, and a small circle between each two lines; 20, a medium-heavy straight line above three arcs, diverging to the right, each alternate line being heavy and each alternate one light, and a small circle between each two. 55

I claim—

The design herein shown for a font of combination type ornaments, consisting of the described series of types numbering from 0 to 20, inclusive, and representing wave and arc 60 ornamentations, as set forth.

Chicago, April 7, 1888.

CHAS. E. HEYER.

Witnesses:

CHAS. S. BURTON,
JOHN R. NETTENSTROUS.